MULTI-FRAME X-RAY DISPLAY

Carl Verne Muffoletto, Baltimore County, Md.
(6100 Everall Ave., Baltimore, Md. 21206)

Filed Sept. 8, 1972, Ser. No. 387,213

Term of patent 14 years

Int. Cl. D24—01

U.S. Cl. D83—1 H

FIG. 1

FIG. 2

FIG. 3

FIG. 4

FIG. 1 is a front perspective view of a multi-frame X-ray display showing my new design;

FIG. 2 is a front elevation taken on a reduced scale;

FIG. 3 is a rear elevation thereof; and

FIG. 4 is a side elevation thereof, the opposite side is a mirror image of the side shown.

I claim:

The ornamental design for a multi-frame X-ray display, as shown and described.
